MYRON W. DOLE, OF BELMONT, MASSACHUSETTS.

LIQUID PUMP.

Application filed March 14, 1927. Serial No. 175,045.

This invention relates to pumps and has for its general object to provide a novel pump for pumping liquid having a temperature approximately that of or slightly below the vaporizing temperature of the liquid and when the available static head on the pump is very small. The ordinary liquid pump in which the inlet valves are opened by the suction produced by the suction stroke of the piston will not function properly when pumping liquid which is at about the temperature at which the liquid will vaporize because the suction produced by the suction stroke reduces the pressure sufficiently so that the liquid will vaporize, the vapor filling the space behind the piston and thus destroying the suction with the result that the pump cylinder will be only partially filled with liquid.

In order to avoid this difficulty I have provided by my invention an improved inlet valve arrangement for a liquid pump according to which the inlet valve is opened by the pressure developed on the pressure side of the piston rather than by the suction produced on the suction side of the piston or by steam pressure taken from the ends of the steam cylinder.

Other features of the invention relate to novel constructions by means of which the inlet valves operate smoothly and without any pounding action and by which the action of the power piston is cushioned at each end of its stroke.

These and other features of the invention will be set forth more particularly in the following description of the selected embodiment of the invention which is illustrated in the accompanying drawings.

In the drawings, Fig. 1 is a fragmentary sectional view of a pump embodying my invention and showing the piston in mid position;

Fig. 2 is a sectional view through the inlet valve device showing the position of the parts after the piston has reached the end of its stroke and is about to start its return stroke;

Fig. 3 is a section similar to Fig. 2 but showing the position of the valves during the down stroke of the piston.

Inasmuch as the present invention relates to the inlet valve feature of a steam-operated liquid pump I have not thought it necessary to show the complete pump structure but have confined the illustration to

the pump cylinder and its piston together with the inlet and outlet valves.

In the drawings 1 indicates the pump cylinder which has therein the pump piston 2, 60 the latter having a piston rod 3 which is connected to any suitable motor device by which the piston is reciprocated in the cylinder. The pump herein shown is a double acting pump and the cylinder has ports at 65 each end, the ports at one end being indicated at 4 and those at the other end at 5. The ports 4 open into a chamber 6 formed in the pump casing and the ports 5 communicate with a chamber 7 also formed in 70 the pump casing.

The pump is provided with two discharge valves 8 and 9 that control discharge ports 10 and 11 leading from the chambers 6 and 7 to a discharge chamber 12, the latter having an outlet port (not shown) which communicates with the discharge pipe. When the piston is moving upwardly as shown in Fig. 1 the pressure developed above the piston will open the discharge valve 8, the discharge valve 9 being closed by its spring and the pressure in the chamber 12. The fluid in the upper end of the cylinder will be forced out through the ports 4 and the discharge port 85 10 into the chamber 12 and from thence through the outlet port. Similarly, when the piston 2 is moving downwardly the pressure below the piston will open the discharge valve 9, the discharge valve 8 being 90 automatically closed.

The parts thus far described are or may be all as usual in liquid pumps and form no part of my present invention which relates to the construction of the inlet valves 95 and piston.

This inlet valve is mounted in an inlet valve chest 14 which is provided with an induction port 15 leading to a source of supply, said port opening into a supply chamber 16. 100 The inlet valve controls communication between the supply chamber 16 and the ports at either end of the cylinder as usual in liquid pumps. The valve herein disclosed, however, is constructed so that it will be shifted 105 from one position to another by the pressure developed on the pressure side of the piston instead of by the suction developed on the suction side of the piston.

The inlet valve structure herein shown 110 comprises two valve members 17 and 18 each in the form of a poppet valve. The valve

member 17 controls a port 19 between the chambers 16 and 6 and the valve 18 controls a port 20 which forms communication between the chambers 16 and 7. Both valves are mounted on a valve rod 21 which is carried by bearings 22, said rod being adapted to move back and forth axially in said bearings. Each valve has a limited movement on the valve rod in the direction of the axis thereof and as shown each valve is formed with the hub portion 23 which fits over and is slidably mounted on a piston sleeve 24 that is rigid with the valve rod. Each valve is acted on by a seating spring 25 and is limited in its movement relative to the valve rod in one direction by its seat and in the other direction by an enlarged end 27 of the piston sleeve 24, said enlarged portion 27 being in the form of a valve adapted to seat against the end 28 of the hub 23. The valve rod 21 carries two collars 26 which engage the valves 17 and 18 as the valve rod is shifted thereby to open the valves.

In installing the pump for pumping a liquid which is at about its vaporizing temperature said pump will be placed slightly below the source of supply so that there will be a small static head in the supply chamber 16.

The operation is as follows. When the pump is at rest and is inactive both inlet valves will be closed by the seating springs 25 as shown in Fig. 2, the distance between the collars 26 on the piston rod being properly proportioned to permit both valves to be seated at the same time. If now the pump is set in operation and the piston begins to move upwardly the liquid above the piston will be subjected to pressure and as the chamber 6 is in free communication with the cylinder the liquid in the chamber 6 will also be subjected to this pressure. The pressure of the liquid against the piston sleeve 24 on the valve rod will be sufficient to move the valve rod downwardly through the valve 17, such movement operating through one of the collars 26 to positively unseat the valve 18 against the action of its spring 25 as shown in Fig. 1. As soon as the valve 18 is unseated the liquid will flow through the induction port 15 and chamber 16 into the lower end of the cylinder thus filling the cylinder with liquid as fast as the piston rises. During this upstroke of the piston the liquid in the upper end of the cylinder will be forced through the discharge port 10 as will be readily understood.

When the piston reaches the upper limit of its stroke and then begins to reverse the pressure in the chamber 6 will be relieved and there will be an instant when said pressure is the same as that in the chamber 7. As soon as this occurs the two springs 25 immediately center the valve rod and close the lower inlet valve 18 as shown in Fig. 2. As

the pump piston 2 continues its descent and pressure is developed beneath the piston this pressure will act on the lower end of the piston sleeve 24 and valve rod and force the same upwardly as shown in Fig. 3 thus positively opening the upper inlet valve 17 so that the fluid under its small static head may flow freely through the induction port 15 and chamber 16 into the upper end of the cylinder. When the piston reaches the lower limit of its movement and then reverses for the upward stroke the inlet valves will again be seated by the springs 25 thus closing both valves and as the upward movement continues the valve 18 will be opened as above described.

It will be noticed that the opening of either inlet valve is derived by the pressure against the end of the piston sleeve in the valve rod which has a relatively small cross-sectional area. The total pressure on this relatively small cross-sectional area will be sufficient to cause the valve to operate properly but is not of such an amount as to cause injurious pounding of the valve.

The auxiliary valve seat on the end 27 of each piston sleeve 24 makes a tight fit with the end 28 of the hub 23 and thus prevents any leakage at this point except during the time the valves are in motion.

In order to cushion the action of the pump piston 2, I will preferably make each end thereof bevelled slightly as shown at 29 so that as the piston approaches the end of its stroke in either direction the ports 4 or 5 will be gradually cut off. By this means the reversing movement of the piston will be cushioned and a smooth running pump will result.

I claim:

1. In a double-acting pump, in combination, a pump cylinder having a piston therein, discharge ports, an induction port, an inlet valve device which in one extreme position opens communication between said induction port and one end of the cylinder while maintaining said induction port closed to the other end of the cylinder, and in the other extreme position closes the first-named communication and opens the second-named communication, and in a central position closes communication between the induction port and both ends of the cylinder, and means tending normally to move said valve device into central position, said valve device when in said central position having a portion at least of each end exposed to the pressure in the corresponding end of the cylinder, whereby the valve device will be automatically centered at the end of each piston stroke and will be positively moved into either extreme position by the pressure developed in the cylinder.

2. In a double-acting pump, in combination, a pump cylinder having a piston there-

- in, discharge ports, a supply chamber, an inlet valve device which in one extreme position opens communication between said supply chamber and one end of the cylinder while maintaining said supply chamber closed to the other end of the cylinder, and in the other extreme position closes the first-named communication and opens the second-named communication, and in a central position closes communication between the supply chamber and both ends of the cylinder, means tending normally to hold the valve device in its central position, and means actuated by the pressure developed in each end 10 of the cylinder to shift the valve device to open the communication between the supply chamber and the other end of the cylinder, whereby the valve device will be automatically centered at the end of each piston stroke and will be positively moved into either extreme position by the pressure developed in the cylinder.
3. In a double-acting pump, the combination with a cylinder having a piston therein and provided with discharge ports, of a supply chamber, two poppet valves controlling communication between the supply chamber and the ends of the cylinder, springs normally holding both valves closed, and means actuated by the pressure developed in each end of the cylinder to open the valve which controls communication between the supply chamber and the other end of the cylinder.
4. In a double-acting pump, the combination with a cylinder, a piston therein and discharge ports, of a valve chest having a supply chamber, two poppet valves controlling communication between said supply chamber and the ends of the chamber, a valve rod on which both valves have a limiting sliding movement, each end of the valve rod being subjected to the pressure in the corresponding end of the cylinder, and springs normally holding the poppet valves closed, whereby during the initial movement of the piston in either direction the pressure developed by the piston in one end of the cylinder will shift the valve rod and thereby open the valve leading to the other end of the cylinder.
5. In a double-acting pump, the combination with a pump cylinder having a piston therein and discharge ports, of a valve chest having a supply chamber, two poppet valves controlling communication between the supply chamber and the ends of the cylinder, springs normally holding the poppet valves to their seats, and a valve-shifting member actuated by the pressure developed in each end of the cylinder to open the valve leading to the other end of the cylinder, said valve device having an area subjected to the cylinder pressure which is considerably less than the area of the valve.
6. In a double-acting pump, the combination with a cylinder having a piston therein and discharge ports, of a supply chamber, two poppet valves controlling communication between said supply chamber and the ends of the cylinder, springs normally holding said valves closed, a valve rod on which the valves have a limited sliding movement, said rod having shoulders against which the valves seat when they are both closed, and each end of the valve rod being subjected to the pressure in the corresponding end of the cylinder.
7. In a double-acting pump, the combination with a cylinder, of a piston therein, ports leading to and from the cylinder, an inlet valve device controlling the supply of fluid to the cylinder, means to cause the pressure produced by the piston in each end of the cylinder to positively operate the inlet valve device to permit flow of fluid to the other end of the cylinder, the ends of the piston being tapered, and the ports being spaced from the ends of the cylinder, so that the piston may over-run them, whereby the final movement of the piston in either direction is checked by the increasing resistance which the piston meets as the tapered portion thereof closes the ports and gradually restricts the outflow of the fluid, said piston being prevented from further movement by the fluid trapped in the end of the cylinder when ports are completely closed.

In testimony whereof, I have signed my name to this specification.

MYRON W. DOLE.
